SLIDE FASTENER CONSTRUCTION

Sanford Rissman, Danville, Ill.

Application July 7, 1950, Serial No. 174,351

2 Claims. (Cl. 24—205.11)

1

The invention relates to improvements in separable fasteners, and more particularly to a slide fastener of the kind having detachable stringers and novel means to facilitate initial attachment of the stringers and movement of the slider preparatory to closing of the fastener.

Separable fasteners of the kind useful especially on garments, and which, therefore, have the stringers detachable, have a stop on one stringer and formed with a socket to be engaged by a post or other socket-engaging member carried on the other stringer end. This is accomplished by first positioning the slider permanently carried on one stringer in abutment with the stop and then passing the post through a channel in the slider and into the socket. When the complementary ends of the fastener stringers are thus connected the slider may then be moved along both of the stringers, and coupling members spaced along adjacent edges of the stringers are coupled or uncoupled by movement of the slider along the stringers. However, difficulty arises frequently in coupling such a fastener because of improper assembly of the detachable parts. As a result, the coupling members will not couple. Such improper assembly may arise from failure to fully insert the post into the socket or failure to have the slider in abutment with the stop when the post is inserted therein.

The present invention seeks to overcome or minimize the possibility of such improper assembly. Accordingly, it is an object of the invention to provide the stringer carrying the post with a tab of relatively stiff material arranged to lie to the rear of the post so as to present a guide surface for the stop and slider during the initial assembly.

Another source of failure during operation of a slide fastener is the frequency with which one or more of the covering flaps or hems of the article carrying the fastener stringers becomes entangled in the slider. At present, it is common practice to secure the portion of the covering flap or hem in the area of the post out of the way of the slider or to omit it entirely. This is, of course, highly objectionable because portions of the metal fastener parts are left unprotected and often cause damage to fine textured material arranged therebeneath. It is, therefore, another object of the invention to provide means to prevent entangling the protective flap or hem normally underlying a slide fastener structure.

Another object is to provide a slide fastener installation embodying the advantages noted hereinabove at little additional cost over the cost

2

of comparable types of slide fastener installations.

Other objects of the invention will appear from the following description and accompanying drawings and will be pointed out in the annexed claims.

In the accompanying drawings there has been disclosed a structure designed to carry out the various objects of the invention, but it is to be understood that the invention is not confined to the exact features shown as various changes may be made within the scope of the claims which follow.

In the drawings:

Fig. 1 is a fragmentary elevational view of a garment or other article showing a slide fastener mounted thereon and in closed position.

Fig. 2 is a view similar to Fig. 1, on an enlarged scale, showing the slide fastener in open or separated position.

Fig. 3 is a view similar to Fig. 2 illustrating the fastener parts in the relative positions assumed just prior to coupling of the stringers, and showing the stop partially in section.

Fig. 4 is a horizontal sectional view, taken substantially on line 4—4 of Fig. 1.

Referring to the accompanying drawings, the separable fastener embodying the present invention includes stringers 11 and 12, each of which has along adjacent edges a plurality of coupling members 13 adapted to be coupled and uncoupled by a slider 14 movable along said stringers in the customary manner. One of the stringers, in the present instance stringer 11, has a stop 15 on one end thereof constituting an abutment for the slider 14 when the latter is in the position substantially as illustrated in Fig. 2. The complementary end of the stringer 12 has a starter, preferably in the form of a post 16, arranged to be engaged with the stop 15 for initially connecting the stringers 11 and 12 together during the closing operation of the fastener. To this end, the stop 15 has a socket 17 therein and, upon referring to Fig. 2, the slider has channels 18 and 19 therein, one of which, in the present instance channel 19, is in registering alignment with the socket 17 when the slider is in abutment with the stop 15.

Initial engagement of the two stringers is effected in the manner shown in Fig. 3. As there illustrated, the stringer 12 having the starter 16 thereon is elevated so as to position the end of the starter 16 at the mouth of the channel 19. The starter then is thrust downwardly into the channel 19 and is seated in the socket 17. Following this initial connecting of the two stringers the slider may then be moved along both stringers

to effect interengagement of the coupling members 13 carried thereby.

Considerable inconvenience and occasional damage result from use of a slide fastener of the character described hereinabove when it is installed in articles such as wearing apparel, especially jackets, wherein the stringers and the coupling members thereon are substantially concealed by front and rear marginal flaps 21 and 22, respectively. This construction is perhaps best illustrated in Fig. 4, in which disclosure the stringers 11 and 12 are stitched between the layers of fabric constituting said flaps. One source of inconvenience arises from the frequency with which either or both of the underlying or rear flaps 22 is entangled with the slider 14 following initial engagement of the stringers. Such entanglement arises because the rear or underlying flap or flaps 22 is of a thickness which permits it to fall inwardly into the path of the slider whereupon a portion of said flap or flaps enters either or both of the channels 18 and 19. Another source of annoyance arises from the difficulty encountered while seeking to insert the starter in the slider channel 19. This difficulty is occasioned by the normal concealment of the starter by the overlying flaps 21 and 22.

Both of these difficulties or inconveniences are efficiently overcome by the provision of a tab 23 in the area of the starter 16. As illustrated, the tab 23 preferably is formed of substantially stiff, firm retaining material, such as leather. The tab 23 may be semi-circular in shape and it has one of its edges firmly secured by the row of stitches 24. This row of stitches may be the row that secures the stringer 12 in place between the flaps 21 and 22 or supplemental stitching may be provided.

The tab is of such size as to project outwardly beyond the free edge of the stringer 12 and above and below the starter 16 thereon. Accordingly, when the two stringers are to be connected, as illustrated in Fig. 3, the slider 14 is rested upon the tab 23 which thereupon functions as a guide surface to facilitate insertion of the starter 16 into the channel 19. The tab also affords a protective covering for the flap 22 located rearwardly of the starter 16. As a consequence, the slider 14 may be engaged with the starter 16 and said slider may be moved upwardly along both stringers to couple the coupling members without catching or otherwise becoming entangled with either or both of the back flaps 22.

Although a specific form of tab 23 has been disclosed in the accompanying drawings for purposes of illustration and has been specifically described in the foregoing specification, it should be understood that the tab may embody any configuration best suited for the particular type of installation and further that said tab may be secured in place by the row of stitches securing the stringer couplers or it may be otherwise

secured or formed as an integral part of its related stringer, without departing from the spirit of the invention or the scope of the appended claims.

5 I claim:

1. In an article having an opening to be closed by a separable slide fastener, a pair of stringers one secured to each edge of the opening, marginal flaps embracing said stringers, engageable means at complementary ends of said stringers for connecting them together, a slider movable along said stringers from adjacent the engageable means to couple coupling members spaced along opposed edges of the stringers, and a tab located between one of the marginal flaps and the engageable means on one stringer, said tab being formed of stiff material and of a size to extend beneath the engageable means on the other stringer when the engageable means are engaged to prevent catching the flaps in the slider during initial movement of the slider while closing the opening.

2. In an article having a slit opening to be closed by a separable slide fastener, stringers, one secured along each edge of said opening, coupling members on said stringers adapted to be interengaged one with another for fastening the stringers together, front and rear flaps on said edges complementary with and embracing the stringers, a slider formed with channels adapted to slidably receive and guide said coupling members to and from interengaging relation with one another, a stop carried by one end of one stringer, a starter carried by an end of the other stringer, said starter and stop being formed to be interengaged to connect ends of the stringers together, and a tab carried by the stringer carrying the starter and arranged to lie between the starter and the rear flap, said tab being fabricated from stiff material and being of sufficient size to extend beneath the stop when the starter and stop are interengaged so as to guide the slider and prevent it from inadvertently catching the rear flap when said slider is initially moved along the stringers.
